UNITED STATES PATENT OFFICE.

CORROLL C. FIGGE, OF CHICAGO, ILLINOIS.

ROOF AND SHINGLE SECURING MEANS.

Substitute for application Serial No. 633,829, filed April 23, 1923. This application filed June 9, 1926.
Serial No. 114,902.

This application is a substitute for applicant's prior application #633,829 filed April 23, 1923 which became abandoned January 1, 1926.

- 5 This invention relates to an improved roof and to the means for securely attaching the shingles thereof. Among the objects of the invention are: to provide an improved form of shingle with a noticeable thickness at the
10 butt increasing the shade line thereof; to simplify the spacing and attachment of shingles in rows or courses; to provide an improved fastening means for engaging different courses of shingles at different relative heights; to provide a common fastening means for a shingle in one course which engages the butt of a shingle in an overlying course and is concealed by the latter when it is in place; and in general, to produce the
15 construction herein shown and described.

In the accompanying drawing, Fig. 1 illustrates a roof with shingles staggered in courses, in accordance with the present invention; Fig. 2 is a section taken on the line 2—2 of Fig. 1; Fig. 3 is a section taken on the line 3—3 of Fig. 1; Fig. 4 is a section taken on the line 4—4 of Fig. 1; Fig. 5 is a perspective of the underside of a shingle; Fig. 6 is a perspective of the fastening device; Fig. 7 illustrates how a shingle may be made to secure additional thickness at the butt end; and Fig. 8 is a perspective of a modified form of clip.

One of the objections to composition roofing is that even though it is coated with finely divided slate, granite chips, or the like it does not have sufficient thickness at the butt to produce a shade line of sufficiently noticeable depth when it is placed on a
35 roof. The result is that no matter how high grade the roofing, it looks flat and cheap. In the present invention this is overcome by forming the individual shingles with a bent edge or edges which may be made as thick as desired, even resembling tiles, and thus producing a shade line of considerable depth.

Another objection to composition roofing is that unless some means is provided for
40 engaging the butt ends of the shingles they are easily warped or bent and in severe weather they are easily bent up by snow or rain, or even by the wind, and soon present an unsightly appearance. If fastening nails
45 are provided through the butt ends they are

rusted or the hole that they make admits water directly through the shingles. The present invention overcomes this objection by engaging the bent under edges of the butts of the shingles thereby holding this portion of the shingles down and at the same time concealing the holding means so that the latter is not objectionable from this standpoint.

Referring now more particularly to the drawings, a shingle 1 constructed in accordance with the principles of this invention is shown in Fig. 5 having two adjacent edges 2 and 3 bent under and either overlapped or bevelled at the corner, as shown in Fig. 5. The outer or weather face of shingles of this type are commonly coated with slate or some other substance resembling stone or tile, and as it is this surface which is outermost, the shingle viewed from the butt edge is of considerable thickness and may even be made to represent tile. In order to increase this effect a block or strip 4, as shown in Fig. 7 may be inserted and held in the bent edge of the shingle, thereby preventing the shingle from collapsing, to preserve and increase this desired effect. In practice it is preferable to have these shingles bent in this manner where they are made, as such bending after the material is hardened causes the surface finish to crack and break away from the body of the shingle.

These shingles are intended to be laid in overlapping courses, the shingles 5 and 6 of adjacent courses being staggered with respect to the other, and the shingles 7 of the next course being in a vertical alignment with the shingles 5 of the second course therefrom.

In order to secure the shingles in place, a fastening device 8 is provided for each shingle. This comprises a single piece of sheet material preferably tinned or galvanized the body 9 of which is substantially rectangular with the two adjacent sides at opposite corners thereof bent upwardly and offset to form sides and extending edges of different height and width. Adjacent sides 10 and 11 are formed with shoulders or offsets 12 less in height than the shoulders or offsets 13 upon which the adjacent sides 14 and 15 are bent. In other words, this fastening device has oppositely extending edges 10 and 11 which are at one height from the

bottom 9 and edges 14 and 15 which are at a different or greater height from the bottom. In the bottom itself are perforations 16 through either one of which a shingle nail 5 17 or other fastening device may be inserted into a roof support 18. In the sides 10 and 11 are other perforations 19 which may be used if desired.

In laying a roof of this kind the lower- 10 most shingles are placed in the desired position with the horizontal corners abutting each other and a fastening device 8 is at- 15 tached to the roofing below the abutting horizontal corners with the projecting edges 10 and 11 extending over the adjacent hori- 20 zontal corners of the said shingles. To ap- 25 ply the shingles of the next course the turned over edges 2 and 3 of the next shingles are slipped over projecting edges 14 and 15 of the fastening device 8 and all 30 the shingles of the next course are located and positioned by this engagement. The same operation is repeated for each course, and it is apparent that after the first course 35 is located in position the other shingles are properly placed and positioned by the en- gagement with the fastening device.

Each fastening device 8 engages not only 30 the shingle to which it is directly applied by inserting the shingle nail through one of the openings 16, but also it engages the ad- 35 jacent upper corners of the shingles of the next course above it by means of the sides 10 and 11, and also it engages the butt of the second course above by means of the sides 14 and 15 which fit under the turned edges 2 and 3 of the shingles. Thus the butt of every shingle is held down at its lowermost extremity and none of the fas- 40 tening devices are visible from the outside of the roofing when the roof is complete.

A somewhat simpler form of clip is shown 45 by Fig. 8 which may be about half the size of the fastening device shown in Fig. 6. In this form the base 21 is substantially 50 triangular in form and rising from two ad- jacent sides 22 are perforated ledges 23 cor- 55 responding to the bent sides 10 and 11. Ex- tends upwardly from these sides 23 are offsets 24 with bent extensions 25 which cor- 60 respond with the sides 14 and 15 of the de- vice 8. This device is used and applied in exactly the same way as the device 8, and the offset extensions 25 extend under the 65 turned under edges 2 and 3 of the shingles at a distance from the point thereof. This device being somewhat smaller and taking less material, is less expensive from the points of manufacture and sale.

One of the most important features of 60 this turned under shingle is due to the fact that by bending the exposed edges or butt ends of the shingle in the manner explained, the edges are sealed against the weather and 65 prevent the deteriorating action of heat and

cold which ordinarily affects the cut edges of such shingles. For example, if the edges are simply cut, they tend to run or slough away under the action of the summer sun, which reduces their sealing, and therefore 70 their waterproofing effect. With the present turned under shingle, the butt or exposed ends are sealed at all times.

Although these very simple forms of shingles and fastening devices are shown, it 75 is obvious that the same principles may be employed with shingles and fastening clips of various forms and shapes without departing from the spirit and scope of the invention. 80

I claim:

1. A concealed single piece shingle holding device for angular butt shingles comprising a box having ledges at different elevations from the bottom thereof for engaging 85 within turned under angular shingle extremitiess and on top of shingles in three different courses.

2. In a roof, a shingle holding device hav- 90 ing a base with opposite ledges at different heights, and rectangular angular butt shin- 95 gles arranged in staggered courses with said butts formed by turning over two adjacent edges inwardly, one of the ledges extending into one of the turned over edges and one of the shingles in an adjacent course ex- tending under another of the ledges for position- 100 ing it.

3. A roof with angular butt shingles in 100 which the butt is formed by turning two ad- jacent sides over inwardly, and fastening de- vices having ledges to engage in the turned over sides of said shingles and with other opposite ledges at a different elevation to po- 105 sition the adjacent corners of similar shin- gles in the next course.

4. In a roof, a separate fastening device with a projecting bent edge invisible when applied, shingles staggered in superposed courses, each shingle having one end formed 110 by bending the edge over inwardly and the bent edge of the shingle being engaged from beneath by the bent edge of the fastening device of the adjacent courses, and means on the device for engaging over the inwardly 115 bent edges of adjacent shingles to position them in a course below.

5. In a roof, a plurality of courses of shingles each shingle comprising an angular butt formed by bending over adjacent 120 edges inwardly to obtain greater thickness, a fastening device for each shingle comprising a member attachable at the upper end of the shingle and having projecting edges which engage under the turned over edges 125 of the shingle butt in a course above thereby covering the fastening device, and other pro- jecting edges to extend over and position shingles staggered in a course below the said butt. 130

6. A roof comprising overlapping courses of shingles the shingles of each course being staggered with respect to those of the adjacent courses, the butt end of each shingle being bent over inwardly to obtain greater thickness and increase the shadow line thereof, and a fastening device for each shingle having projecting ledges at different elevations from the bottom thereof, the upper ledges positioning and overlapping the adjacent edges of the course next above that to which the fastening device is applied, and the lower ledges engaging in the overturned edge of the butt of the shingle in the second course above that to which the fastening device is attached.
- 10 7. A shingle positioner and holder for angular butt end shingles which are turned under at the angular butt end, said holder comprising a perforated attachment base
- 15
- 20

with opposite outwardly turned ledges at different elevations, one ledge to engage over the edge of a shingle in the course next above that to which the base is applied, and the outer ledge to engage within the turned 25 under butt end to position and hold it down without being visible from the exterior side of the roof.

8. A roof with rectangular shingles having two adjacent edges turned over inwardly 30 to form a thick angular butt, and a diamond patterned roof, the shingles of one course being staggered with respect to the adjacent ones, and a one piece fastener having a ledge adapted to be inserted under the turned over 35 edge of one butt to hold it down and other projections to extend over the edges of adjacent shingle ends in a course below to hold them in place.

CARROLL C. FIGGE.
